UNITED STATES PATENT OFFICE.

FRANK J. TRCKA, OF OMAHA, NEBRASKA.

WORK-CLAMPING TABLE.

1,245,638.

Specification of Letters Patent.

Patented Nov. 6, 1917.

Application filed August 15, 1917. Serial No. 186,302.

To all whom it may concern:

Be it known that I, FRANK J. TRCKA, a citizen of the United States, residing at Omaha, in the county of Douglas and State 5 of Nebraska, have invented certain new and useful Improvements in Work-Clamping Tables, of which the following is a specification.

My invention relates to a work-bench or work-clamping table adapted for setting up and holding framework of a rectangular form, such as grain doors and the like, said bench or table being provided with clamping-means under the control of workmen at 10 opposite portions of the table whereby the strips or pieces which enter into the construction of the door or other rectangular form may be securely clamped together, while being supplied with battens or other 15 pieces while the parts are being nailed together to form a strong ever and tight door and one which will prevent the leakage of grain or other fine material when the door is used in a grain car, or the like.

Various work-holding devices have heretofore been employed in the construction of grain-doors and other rectangular forms and means have been furnished these devices for clamping together the parts which enter 20 into the grain door or other form construction. The device I am about to describe has been very extensively employed and has been found very satisfactory and possessing 25 advantages which the devices of the prior art apparently do not have, and among these are the following:—

The pressure comes from the opposite side from the nailer so as not to interfere with his work; the arrangement is such that 30 the door or other form can be engaged and released with very little loss of time, which is quite important in the manufacture of grain doors; also, the cost of making the present device is small and the device is 35 strong and does not readily get out of order or necessitate repeated repairs.

In the accompanying drawings forming part of this specification and in which similar reference characters indicate like parts 40 in the several views;

Figure 1 is a perspective view of a work bench or table provided with my improved clamping mechanism.

Fig. 2 is an end view of the same.

In carrying out my invention, I provide 45 a substantial framework of any desired di-

mensions and of such construction as to give stability thereto. In the form of device shown, the framework consists of longitudinally extending bars, 10, appropriate 60 cross bars, 11, and upright bars, 12, these several bars being securely nailed or otherwise secured together so as to give great 65 rigidity to this supporting frame structure. The dimensions of this frame will vary 70 according to the dimensions of the door or structure to be supported therein, and hence it will be understood that I am at liberty to use any length and width of frame which may be desirable for an intended purpose. 75

On top of the upper cross bars, 11, which as shown are at the ends and middle portions of the supporting frame and which bars may be of any desired number disposed crosswise along the length of the 80 frame, is placed the table or working surface, 13, which may be formed of boards, but which I prefer to make of a metal plate adapted to clench the nails driven through the boards assembled thereon, said plate 85 constituting a suitable smooth tabular surface upon which the strips or boards which enter into the construction of the grain door or other rectangular structure to be built, are laid, this tabular surface being securely 90 fastened to the cross bars, 11, or otherwise rigidly secured in place.

At one side, it will be observed that the upper ends of the uprights, 12, are extended above the plane of the top surface of the 95 table, 13, and hence the inner surfaces of these projecting ends may form abutments, or guides for the side edge of the initial door board or strip, it being understood that one end of the table is provided with 100 another abutment or stop, 14, against which the ends of the boards to be assembled and nailed together abut. The opposite end of said table is without stop and is open so that should there be any irregularity in the 105 length of the boards used, the projecting ends of these boards may be sawed or dressed uniformly by an attendant.

Instead of utilizing the projecting ends of the uprights as stops or abutments for the side edges of the initial board of the proposed door, I prefer to secure along the longitudinal side of the table a bar, 15, which fits closely against the inner surface of the 110 projecting portions of the post and is secured in place and to the table by nails or other fastenings, the inner surface of this

board forming the stop and guide for the side edge of the initial board of the proposed door-structure.

The opposite side of the table is devoid of longitudinally extending bar or stop so as to permit the boards or strips which enter into the proposed door-structure to be assembled from this side and to be laid together edge to edge over the surface of the table, and in order to firmly hold these boards in tight edgewise relation, and uniformly so that they can be appropriately nailed or otherwise secured together, I employ a clamping mechanism of novel form and one embodiment of which is illustrated in the drawing. This clamping mechanism consists of a lever, 16, at each end of the table, said lever being pivotally secured at a point intermediate its ends, but nearer the upper end than the lower, to the upper portion of the corner uprights at one side of the table, said lever being extended downwardly to a point at or near the lower portions of the corner posts at the opposite side of the table and being provided with an extension 17, which form substantially a treadle for an operator's foot. In the form of device shown, the treadle is an extension of a horizontal bar, the opposite end of which is connected by a vertical bar, 18, to the lever at a point below its pivotal center. This construction gives added weight to the free end of the lever and thus facilitates the ease with which the lever may be operated.

It will be understood that one of the before described levers is disposed at each end of the supporting frame, the upper ends of these levers being connected by a bar, 19, to the inner face of which is secured a clamping bar, 20, which preferably stands on edge and has sufficient height that when it is closed against the adjacent edge of the table it will project above the plane of the face of the table and of the boards or strips assembled thereon so that the boards are confined along one side by this clamping strip and along the opposite and corresponding side by the bar, 15, and at one end by the cross-bar, 14. This cross-bar, 14, has a recess, 14', which enables the operator to insert the claw of his hammer, or a like tool, and force the assembled door endwise, to thereby enable an operator at the other end of the table to readily remove the door and load it onto a truck or otherwise.

In operation, the weight of the clamping bar is utilized to cause this bar to normally drop away from the adjacent edge of the table, although the lever may be positively raised to this same purpose, if desired. Generally the clamping bar has sufficient weight to overcome the weight of the lever and hence when the pressure of the operator's foot is removed from the treadle portion of the lever, the clamping bar drops away from

the table and the boards or strips which are to enter into the door construction are assembled on the table edge to edge, the initial board bearing edgewise against the longitudinal stop or guide, 15, and the ends of the several boards abutting against the end stop 14. When the desired number of boards have been assembled, the lever-mechanism is operated to bring the inner face of the clamping bar, 20, against the outer edge of the nearest board or strip and then the operator, one at each side or end of the table, by pressing upon the treadle-portion, 17, of the lever will cause the clamping bar to securely press the boards into intimate edgewise relation, and while the boards are in this condition, the nailers may apply the battens, if desired, and nail the same and the several boards securely together. When this has been accomplished, the lever mechanism may be released when the clamping bar automatically drops away from its side of the table and the assembled door may be readily and quickly removed.

From this description it will be understood that there are two nailers stationed at opposite portions of the table, and when the face boards for the proposed grain-door are laid on the table, 13, these nailers put their weight on the lever portions of the clamp and thereby draw the clamp tightly against the boards, forcing them closely together, to thereby prevent the grain or other fine material from leaking out from the ends of the door when said doors are assembled in the grain or other car, a condition which is present in many of the grain doors now in use and has been the source of complaint and of claims against railroad companies for loss of grain in transit.

Among the advantages which can be urged for the present simple construction are: The position of the clamp does not in any manner interfere with the work of the nailers, who are able to readily apply and release the clamp from each end of the table, thereby saving time and increasing the output of the device 25 to 50%. The cost of the clamp is very small and in fact the construction is such that the table and parts thereof can be readily made by the nailers themselves.

The clamp is strong and seldom needs repairs, and when repairs are necessary they may be easily done with a saving of considerable time.

Having thus described my invention what I claim as new and desire to secure by Letters Patent is:—

1. In a device of the character described, the combination with a supporting framework having an abutment or stop along one of its upper sides and an abutment or stop across one end, and a table or surface on which boards or strips are assembled edgewise to make up a rectangular structure, of

a clamping mechanism comprising levers at opposite ends of the framework and pivotally secured thereto, the upper ends of said levers being connected together, and a 5 clamping bar fixed to the upper ends of the levers and extending parallel with the adjacent side of the table and adapted to be moved toward and from said table to engage and release an adjacent board or strip 10 thereon.

2. In a device of the character described, the combination with a supporting framework, comprising longitudinal and cross-bars and end and intermediate uprights, a 15 fixed table, and stops extending along one end and one side of the table, the opposite side and end of the table being devoid of stops, of a lever at each end of the framework pivotally secured below the table and 20 having the lower ends serving for the application of an operator's foot, a bar extending between the upper ends of the le-

vers, and a clamping-bar secured to the last-named bar adapted to close against the contiguous open side of the table and to engage 25 and securely clamp in edgewise relation boards or strips assembled on said table.

3. In a device of the character described, the combination with a supporting framework, comprising longitudinal and cross- 30 bars and end and intermediate uprights, a fixed table, and stops extending along one end and one side of the table, the opposite side and end of the table being devoid of stops, of a lever mechanism pivoted on the 35 upper portion of the framework, and a clamping bar on the upper end of the lever mechanism and movable thereby into and out of engagement with the adjacent side of the table and adapted to edgewise clamp 40 together boards arranged in abutting relation on the table.

In testimony whereof I affix my signature.

FRANK J. TRCKA.
